BED SPRING SUPPORT

James Lee Carver and Forrest Arthur Chace,
Birmingham, Ala.

Application September 16, 1953, Serial No. 26,826

Term of patent 14 years

(Cl. D5—2)

To all whom it may concern:

Be it known that we, James L. Carver and Forrest A Chace, both citizens of the United States and both residents of Birmingham, in the county of Jefferson and State of Alabama, have invented a new, original, and ornamental Design for a Bed Spring Support, of which the following is a specification, reference being had to the accompanying drawing, forming a part hereof.

Fig. 1 is an isometric view of a bed spring support embodying our new design;

Fig. 2 is a side elevational view thereof;

Fig. 3 is a plan view thereof; and,

Fig. 4 is a rear elevational view, that is, an elevational view looking at the hook end of the support.

We claim:

The ornamental design for a bed spring support, as shown.
